UNITED STATES PATENT OFFICE.

LOUIS A. WILKINSON, OF DES MOINES, IOWA.

GUIDE FOR MARKING BALLOTS.

No. 911,100.

Specification of Letters Patent.

Patented Feb. 2, 1909.

Application filed September 4, 1908. Serial No. 451,767.

To all whom it may concern:

Be it known that I, LOUIS A. WILKINSON, of Des Moines, in the county of Polk and State of Iowa, have invented certain new and useful Improvements in Guides for Marking Ballots; and I do hereby declare the following to be a full, clear, and exact description of the invention, such as will enable others skilled in the art to which it appertains to make and use the same.

My invention contemplates improved means for marking election ballots, the primary object in view being to enable illiterate voters, or those unfamiliar with the names of the candidates or the propositions to be voted for, to express their choice without having to read the ballot.

A further object is to enable each voter to preserve a record of his ballot as a means of recalling exactly how he voted and for use in the event of fraud by the election officials.

The invention is designed for use in connection with the Australian ballot, as the system is known in which the names of all the candidates appear on each ticket or ballot.

Broadly stated, my invention comprehends a perforated sheet which is laid upon the official ballot, the perforations disclosing the squares on the ballot within which the voter is to make his mark, the squares being, as is well understood, beside the names of the candidates or the propositions to be voted for. The perforations in the sheet are located at such points as may be necessary in order to bring them into register with such of the squares on the ballot as will indicate the previously expressed wish of the voter.

The invention further contemplates means for holding the perforated sheet and the ballot together and for the voter making a record of the vote which he may cast.

In the accompanying drawings, Figure 1 shows a specimen of an official ballot together with a marking device embodying my invention. Fig. 2 shows the device in its folded position, parts being broken away. Fig. 3 is a section on line 2—2, Fig. 2. Fig. 4 shows the device folded with a punch in dotted lines.

Referring to the drawing, 1 designates a ballot having the usual arrangement of designation of parties and their respective candidates, each of the names having a square space 2 beside it. I have shown the marking means consisting of a sheet folded to form

two sections between which the ballot may be held. The lower section 3 is shown provided with a pair of flaps 5 secured near its side edges. These constitute a guide in which the ballot 1 may be held. Each flap 5 has printed thereon a pointer or arrow 5^a which serves as an indicator for properly positioning the ballot between the leaves. The upper section 4 has holes or perforations 6 formed therein, and when this section is folded down over the ballot-holding section the holes or perforations will be directly over the squares 2 which the voter wishes to mark. Obviously these perforations will be made according to the wishes of the voter, the illustration showing a "split" ticket, that is, one by which the voter expresses his preference for the candidates of one party for some of the offices and those of another party for other offices.

Any preferred means may be employed for indicating on section 4 the points at which the perforations are to be made, such section having marginal lines 6^a spaced apart to a distance corresponding to the width of the ballot, or the dimensions of the entire section may correspond to those of the ballot. By this means the location of the squares 2 to be marked may readily be duplicated on the guiding section. To aid in making the perforations, especially those near the center of the guiding section, I have provided a punch 7, shown in Fig. 4, having its arms curved outwardly as at 8. This formation permits of the guiding section being folded within the arms so that the punch proper, indicated at 9, may be brought over the point at which the perforation is to be made.

I also provide for the voter maintaining a record of his vote. For this purpose I have shown in Fig. 2 the lower or ballot containing section 3 formed with a pocket to contain a sheet of carbon paper 10 having its coated surface down or against the inner face of the back of the pocket. By this means the marks made in the squares 2 of the superposed ballot 1 are duplicated on the back of the pocket. By scoring the sheet at its fold, as at 12, the sections 3 and 4 may readily be separated and a subsequent comparison of the carbon marks with a copy of the ballot will enable the voter to show how his ballot was cast.

It will be apparent that the sections may be made of paper and folded so as to enable the voter to conceal the evidence of his pref-

erence and that the invention provides simple and inexpensive means for attaining the purpose contemplated.

I claim as my invention.

- 5 1. Ballot marking means comprising, in combination with a ballot, a guide designed to be laid over the ballot, said guide having perforations disclosing the part or parts of the ballot to be marked according to the 10 previously expressed wish of the voter.
- 15 2. Ballot marking and recording means comprising, in combination with a ballot, two sections between which the ballot may be held, one of said sections being designed 20 to be laid over the ballot and having perforations disclosing the part or parts of the ballot to be marked according to the previously expressed wish of the voter, a carbon sheet, and means for retaining the latter in place beneath the ballot.
- 25 3. Ballot marking and recording means comprising, in combination with a ballot, two sections between which the ballot may be held, one of said sections being designed 25 to be laid over the ballot and having perfor-

ations disclosing the part or parts of the ballot to be marked according to the previously expressed wish of the voter, and flaps on the other section forming guides for positioning the ballot.

4. Ballot marking and recording means comprising, in combination with a ballot, a sheet folded to form two sections between which the ballot may be held, means on one section for securing said ballot, said section 30 having a pocket, and a carbon sheet located within such pocket, the other section being perforated to disclose the part or parts of said ballot to be marked according to the previously expressed wish of the voter, said 35 sheet being scored at the junction of the two sections.

In testimony whereof, I have signed this specification in the presence of two subscribing witnesses.

LOUIS A. WILKINSON.
